UNITED STATES PATENT OFFICE

GUSTAF A. JOHNSON, OF BARNEVELD, NEW YORK

CASTING REEL

Application filed November 4, 1926. Serial No. 146,250.

My invention relates to a casting reel, and I declare the following to be a full, clear, concise and exact description thereof sufficient to enable anyone skilled in the art to which it appertains, to make and use the same; reference being had to the accompanying drawings in which like reference characters refer to like parts throughout the specification.

10 The object of the invention is to provide a reel for casting that will be compact; equipped with a self-oiling free winding spool; with an adjustable unlimited friction device to prevent excessive strains from snapping the line; with a rocking lever for demeshing certain gears, whereby to allow the winding spool to turn freely; with a brake for preventing the rotation of the spool; means for adjusting and releasing said brake; and a detachable level winder to prevent piling up of line when winding or unwinding the same. These and other advantages will appear by referring to the drawings in which:

15 Fig. 1 is a perspective view of the reel.

Fig. 2 is a side elevation of the reel.

Fig. 3 is a detail perspective view of a rock member and immediate parts used.

20 Fig. 4 is a detail perspective view showing the interior of the casing, parts being removed therefrom.

25 Fig. 5 is a detail perspective view of a hub with cam employed.

Fig. 6 is a detail plan view of a cam and immediate parts used.

30 Fig. 7 is a detail perspective view of a rocking pawl and immediate parts used.

Fig. 8 is a detail perspective view of the spur gear and immediate parts used.

35 Fig. 9 is a detail perspective view of the upper part of the casing looking toward the inside surface thereof.

Fig. 10 is a central vertical section of the reel enlarged.

40 Fig. 11 is a detail perspective view of the drag member used.

Fig. 12 is a detail perspective view of the screw bolt used.

45 Fig. 13 is a detail perspective view of a spur gear, shown also in Fig. 8.

Fig. 14 is a detail perspective view of a cap used.

Fig. 15 is a detail perspective view of a spring used.

Fig. 16 is a detail perspective view of a spool used.

Fig. 17 is a detail perspective view of a line vibrator and immediate parts used.

Fig. 18 is a detail view of a locking pawl and lever for actuating the same and showing their rock positions in dotted lines.

Fig. 19 is a detail perspective view of an annular nut employed.

Fig. 20 is a detail perspective view of a cap employed.

Referring more particularly to the drawings, the device embodies a casing comprising a base part 1 having an annular wall 2 adapted to interfit along its upper edge 3 with the corresponding depending edge 4 of top part 5. Apertures 6 are made in said parts, whereby to lighten the reel as much as possible. Top part 5 is equipped with a rectangular raised portion 10 extending diametrically across the top and for housing certain members, hereinafter described. Likewise, lower or base part 1 is equipped with an annular depression 11 for housing certain other members to be described. Said parts 1 and 5 are made with interfitting edges. Vertical slots 7, 7 are cut in the upper edge of wall 2 to form a tongue 8 adapted to rest in recess 9 of top part 5 to aid in interfitting said parts 1 and 5 in proper assembled position.

A line winding spool 15 is mounted to rotate between base part 1 and top part 5. To this end, a vertical shaft 16 is disposed through the center of the device, on which shaft 16 said spool 15 turns. Spool 15 comprises upper and lower plates 17 and 18 that are spaced apart and by spacing sleeve 19. Disk plate 21 is disposed on the top of plate 17 and is adapted to aid in making an oil tight joint with contiguous parts. Three headed screws 22 are projected through apertures in disk plate 21 and extend down through the chamber 23 formed by spacing sleeve 19, through apertures in the lower base plate 24 of sleeve 19, through

plate 18 and into the threaded apertures in clicker gear 25. The heads of screws 22 are beveled and counter sunk in plate 21 to fit flush with the upper surface thereof.

5 In order to retard the rotation of spool 15 gear 25 is engaged by click or tooth 26 pivoted at 27 to longitudinally movable member 28 slidingly mounted in a guide way formed in disk 30 that is riveted to 10 the upper surface of depression part 11 of base 1. The sides of member 28 are beveled whereby to prevent said member from falling out of the guide way in disk 30. Member 28 is urged normally towards the center 15 of the reel, whereby tooth 26 will engage gear 25 by a wire spring 31 doubled back upon itself. The part 32 of spring 31 is held by a rivet 33 to base 1, whereas, the free ends 34, 34 engage opposite sides of 20 tooth 26 and are bent to conform to the curvature thereof, whereby said ends will resist any pressure tending to push tooth 26 away from the center of the reel. Said ends will allow the free end of tooth 26 to turn 25 slightly on its pivot.

However, tooth 26 may be forced radially away from the center and from engaging gear 25 by cam 35 pressing against the inner end of longitudinally movable member 28. 20 Cam 35 is made integral with hub member 36. A flange 37 also made integral with hub 36 partially surrounds said hub and aids in holding the same concentrically with aperture 38 made in disk 30. Hub member 36 is 35 turned, whereby to bring cam 35 against the contiguous edge of movable member 28 by its connection with shaft 16 which is squared at 41 to fit the square shaped upper part of the hollow interior of hub 36.

40 The upper end of shaft 16 has attached a crank or handle 42 that is held thereto by a pin 43. Handle 42 is held temporarily in either one of two positions by means of notches 44, 45 formed in the upper edge of hollow cylinder 46. When handle 42 rests in notch 44, the end of movable member 28 will rest between cam 35 and the contiguous edge 47 of flange 37 or part 48 of hub 36, whereby the free end of tooth 26 50 will engage the teeth of gear 25 and when handle 42 rests in notch 45, the end of movable member 28 will rest against cam 35, whereby the free end of tooth 26 will be moved back and away from the teeth of 55 gear 25.

It will be observed that the upper edge of cylinder 46 is beveled at 48, 48 to allow handle 42 to slip in and out of notches 44 and 45 in an easy manner. A coiled spring 60 50 disposed about shaft 16 and bearing at one end against a collar 51 fixed to shaft 16 and at the other against a shoulder on cylinder 46 tends to force handle 42 normally into notches 44 and 45 when turned there 65 opposite.

Cylinder 46 is held to the upper surface of rectangular raised portion 10 of top part 5 by a second cylinder 52, having a flange 53. Cylinder 52 is projected up through an aperture made in the upper surface of raised portion 10. Cylinder 46 is provided with a recess 54 adapted to allow said cylinder to be pressed down over cylinder 52 in a tight fitting manner, whereby to hold said cylinders 46 and 52 rigidly in place with respect 70 to the surface of portion 10. Cylinder 46 is extended laterally at 55. A screw bolt 56 is projected through an aperture in extended part 55, and mounted in the surface of portion 10 to prevent cylinder 46 from 75 turning. A second recess is made at 57 in extended part 55 for the swinging of pawl or locking dog 58 that is pivoted to a shaft 59 mounted in the side of cylinder 46. A sleeve 60 is mounted also on shaft 59 to hold 80 pawl 58 in spaced relation to the surface of cylinder 46. The lower corner 61 of pawl 58 is milled off slightly, whereby to cover the adjacent edge of rock plate 62, when 85 said plate 62 is lying flat upon the upper surface of portion 10, to thereby prevent said plate 62 from accidentally raising before predetermined time. Moreover, the lower end of pawl 58 is moved upon plate 62 as well as away therefrom by rocking member 63, which has an open recess 64 up through 90 which pawl 58 projects. The sides of member 63 adjacent recess 64 engage the enlarged tapering parts 65 and 66 of pawl 58, whereby to rock pawl 58 on and off of the edge of 95 plate 62. Plate 62 is equipped with two depending lugs 67, 67 having apertures for the projection of bearing shaft 68 that also projects through bearings in depending lugs 100 69, 69 formed by cutting the surface of 105 portion 10 and bending down lugs 69.

A hollow stationary cylinder 70 is mounted to plate 62 by the aid of cylinder 71 having a flange 72 counter sunk in plate 62. Cylinder 71 is projected upward through an aperture in the surface of plate 62. Cylinder 70, on the other hand is adapted to be pressed down over cylinder 71 in a tight fitting manner, whereby to hold said cylinders 70 and 72 stationary and in place with 110 respect to the surface of plate 62. A cap 75 having external threads 76 made thereon is adapted to fit loosely over cylinder 71; whereby to turn thereon. Cylinder 71 is adapted to contain plug 73 that is projected 115 up through the center thereof. A flange 74 is formed integral with plug 73.

The upper surface of cap 75 has an oblong shaped recess 80 adapted to receive the upper end 81 of plug 73. Said upper end 120 81 is angled to conform to the oblong shape of recess 80, whereby to cause said cap 75 to rotate with plug 73. Furthermore, plug 73 is reduced and threaded at 83 for mounting 125 of a circular nut 84 having grooves in its 130

periphery adapted to be engaged by lock tooth 85 made on the end of coiled spring 86 that is mounted on the lateral wall of cap 87. Cap 87 has a roughened peripheral edge 88 to aid in turning the same. The shank 89 of crank handle 90 has an angled recess to fit over the angled part 81 of plug 73 between cap 75 and circular nut 84; a headed screw bolt 92 projects up through and is 10 threaded to the central recess in plug 73. The extreme upper end of bolt 92 is angled to engage the angled aperture 93 made in the top surface of cap 87, whereby the turning of cap 87 will turn bolt 92 and 15 move it longitudinally with reference to plug 73. A nut 94 is screw mounted to the extreme upper end 95 of screw bolt 92, the threads of the bolt being continued on the sides not milled off to make its upper end 20 angled. The lower headed end 96 of screw bolt 92 is conical in shape to engage a counter sunk correspondingly formed aperture in disk plate 97 which is concaved and yielding and bears against the reduced central surface 98 of spur gear 99 with more or less pressure as determined by the turning of bolt 92 by means of cap 87. Leather pieces 100 are plugged into apertures made 25 in the central surface 98 of gear 99, whereby to increase the friction between the surfaces 98 of gear 99 and disk plate 97.

A line vibrator 101 is disposed circumferentially across the line passage opening of wall 2 and the alined opening 102 of plate 35 103 that is attached by screw bolts 104, 104 to said wall 2 of the lower casing 1. The free ends of vibrator 101 are held loosely in sockets 106, 106 fastened to wall 2 at widely different positions, whereby vibrator 101 can 40 be reciprocated across the space occupied by openings 102 and 103. Vibrator 101 being made of a resilient wire, will allow its free ends to spring into sockets 106, 106, whereby the same will be held thereto and at the 45 same time permit vibrator 101 to rock on its ends as a fulcrum.

The mechanism for actuating vibrator 101 embodies an arm 107 having a bifurcated end 108 adapted to engage vibrator 101 in a 50 detachable manner. The upper horizontal part 109 of arm 107 is widened and provided with an aperture adapted for the projection of a pivot 110 extending from bracket 111 upstanding and fastened to plate 62 which pivot 110 serves as a fulcrum for the 55 rocking motion of arm 107. The free end of horizontal part 109 of arm 107 has an elongated recess 112 through which projects stud 113 extending from the end surface and adjacent the periphery of worm 114. Worm 114 has one end resting in an aperture in bracket 115 fixed to plate 62. The 60 opposite end of worm 114 is reduced to form an arbor 116 that has a bearing in bracket 118a also mounted to plate 62. Threads 119

of worm 114 engage threads 76 of cap 75, whereby the turning of cap 75 will cause worm 114 to revolve and arm 107 to rock on its fulcrum 110. The rocking of arm 107 will actuate vibrator 101. It will be observed that the horizontal part 109 of arm 107 is located between bracket 111 and the end surface of worm 114, whereby to hold said worm 114 from moving endwise with respect to its bearings.

A member 116a having a part 117a that lies parallel and a little outside of and above vibrator 101 is adapted to cooperate with said vibrator 101 to hold line 77 therebetween. The upper horizontal part 118 of member 116a is provided with an elongated recess 119 through which projects one end of a wire 120 that forms a pivot. Part 118 extends beyond the end of wire 120 and is curved downward and pivoted at 123 to a 75 stud projecting laterally from the side surface of raised portion 10 of top part 5. Portion 10 is cut away at 121 to clear the end of the curved portion of part 118 of member 116a.

Plate 62 is equipped also with two upstanding brackets or ears 125, 125 formed by bending the surface thereof upward. Ears 125 have in each instance an elongated recess 126 and are in parallel relation to other ears 127, 127 formed by bending down the opposite sides of rock member 63. Wire 120 above mentioned having its ends bent to form pivots that project through suitable apertures in ears 127 and the elongated recesses 126 of ears 125 extends rearward in the form of a yoke to clear cylinder 70.

Rock member 63 is equipped with two depending brackets or ears 128, 128 that are formed by bending down the contiguous surface. Ears 128 project through suitable apertures 129 made in the top surface of raised portion 10 of the casing and aline with ears 130, 130 likewise formed by recessing the casing of raised portion 10 and bending down the cut portions. A wire shaft 131 extends through suitable alined apertures in the ears 128 and 130 thus formed. A spring 132 bent in the form of a rectangle is disposed beneath rock member 63. The free ends 133, 133 of spring 132 are bent about shaft 131 and rest against the lower surface of rock member 63 at one end and against the upper surface of raised part 10 at the other, whereby to force the handle part 134 of rock member 63 normally upward.

An adjustable drag member 135 is fulcrumed upon wire shaft 131. Drag member 135 has a bifurcated part with two contact 125 members 136, 136 adapted to hold leather fillings 137, 137 which rest against the upper surface of plate 17 of spool 15. A tongue 138 having an angle bent therein, as at 139, is formed also as part of drag mem- 130

ber 135. An aperture 140 is made in the end of tongue 138. A headed bolt 141 having external threads thereon projects up through aperture 140 of tongue 138 and engages corresponding threads in boss 142 fastened to the upper surface of raised portion 10. Bolt 141 projects also up through an aperture in rock member 63 and has a knurled cap 143 mounted on its upper end in such manner as to turn therewith. Turning of bolt 141 by means of cap member 143 to approach nearer to the under surface of raised portion 10, will force leather fillings 137 of members 136 more closely in contact with the upper surface of plate 17 of spool 15 to increase the drag on the spool 15 or bolt 141 can be turned in the opposite direction to decrease said drag.

Handle part 134 of rock member 63 is equipped with an opening at 144 which aligns with a similar opening 145 made in the casing of raised portion 10. Openings 144 and 145 will expose partially the upper surface of plate 17 of spool 15, whereby the operator's thumb used in rocking member 63 to demesh gear 99 and pinion 150 can be projected through said openings 144 and 145 to stop the rotation of spool 15.

Spur gear 99 is adapted to mesh with pinion 150 fixed to turn with the upper reduced end of central hub 151 carrying at its lower end and formed integral therewith gear 25. Hub 151 is projected through central apertures in plates 17, 18 and 21 and is surrounded by a spacing sleeve 152 disposed between plates 17 and 18.

A lubricating chamber 23 is formed between the outer surface of sleeve 152 and the inner surface of sleeve 19. In order that the oil might penetrate between the contiguous surfaces of hub 151 and sleeve 152 a V-shaped peripheral groove 162 is formed in the outside surface of hub 151, which groove is connected to chamber 23 by an aperture 163, made in spacing sleeve 152. Furthermore, the oil is permitted to reach shaft 16 through conduit 164 made in central hub 151 and connecting with V-shaped groove 162.

Port 165 that extends through the lower surface of spacing sleeve 19, plate 18, and the central body part of gear 25, is adapted for the admission of the lubricant to chamber 161. A spring pressed ball valve 166 normally closes the opening to part 165.

Three arms 170 are pivotally mounted to lower part 1 of the casing at 171 to aid in holding parts 1 and 5 together, when said parts are assembled. Arms 170 have in each instance upper and lower horizontally disposed walls 172 and 173 respectively, which with the side wall 174 form closures to clamp parts 1 and 5 together. They have also in two instances chambered parts

175 to clear the ends of vibrator 101 and sockets 106.

The operation of the reel is effected by attaching line 77 to the hub of spool 15. This can be done easily by swinging arms 170 on their pivots away from annular wall 2 of part 1 as seen in Fig. 4 and then separating parts 1 and 5 and removing reel 15. Parts 1 and 5 can be re-assembled correctly by directing tongue 8 of edge of wall 2 towards recess 9, of top part 5. Spool 15 will be turned by actuating handle 90. If the operator wishes the click on or the meshing of tooth 26 with gear 25, he will turn handle 42 to engage notch 44. He can release the click by moving handle 42 to notch 45 or by moving it along the upper edge of hollow cylinder 46 between notches 44 and 45 from whence it will be moved automatically into notch 45 by handle 42 when it is rotated. In this releasing position of handle 42, spool 15 will turn freely in either direction by moving crank handle 90. As crank handle 90 is turned line vibrator 101 will be reciprocated by the action of threads 76 of cap 75 on threads 119 of worm 114 which will move stud 113 in a circle to cause the rocking of arm 107 and therefore of vibrator 101 to prevent line 77 from piling on spool 15. In this particular vibrator 101 will be aided by member 117a. Moreover, member 116 will be elevated clear of vibrator 101 when member 63 is rocked to demesh gear 99 from pinion 150 by its intermediate pivotal connection with rocking member 63 at 125, 125.

Spool 15 is left to rotate freely in either direction by itself by rocking member 63 usually with the thumb to thereby rock plate 62 to elevate gear 99 out of mesh with pinion 150. By advancing the thumb a little further it can be projected through openings 144 of handle 134 and opening 145 in raised portion 10 and onto plate 17 to stop the rotation of spool 15. Immediately the pressure of the thumb on rocking member 63 is withdrawn the same will return to normal position under influence of spring 132.

In the event that an abnormal pull should occur on line 77, when turning spool 15 to reel in said line, a break of said line will be prevented by the sliding of disk plate 97 over the surface of gear 99, whereby the further turning of crank handle 90 will not turn gear 99 and hence pinion 150 and spool 15.

A member 180 is attached to the lower surface of depression 11 for assembling to a fishing pole not shown.

Having thus described my invention, what I claim as new and desire to secure by Letters Patent, is as follows:

1. In a casting reel, a spool for winding the fishing line thereon, a gear adapted to turn with said spool, a second gear enmeshed

with said first named gear, a rock member for carrying said second named gear and another rock member for actuating said first named rock member, to withdraw said gears, 5 whereby to allow said spool to rotate at will.

2. In a casting reel, a rotatable spool, a casing for enclosing said spool, a pinion mounted to turn with said spool, a rock gear meshing with said pinion, means for rotating said rock gear, whereby to turn said spool and a lever fulcrumed on said casing, and mounted to move in a plane at right angles to the spool for rocking said gear clear of the pinion whereby to allow said 15 spool to rotate at will.

3. In a casting reel, a rotatable spool, a pinion mounted to turn with said spool, a gear for rotating said spool, rock means for releasing said gear from said pinion, where- 20 by said spool will rotate at will, and a locking pawl actuated by said rock means, to hold said gear in pre-determined position.

4. In a casting reel, a rotatable spool, a pinion adapted to turn with said spool, a gear enmeshed with said pinion, a rock mem- 25 ber for actuating said gear free from said pinion, whereby to allow said spool to rotate free of said gear, a locking pawl for holding said gear in pre-determined posi- 30 tion and means on said rocking member to actuate said locking pawl to releasing position.

5. In a casting reel, a rotatable spool, a shaft projecting through said spool, a pinion adapted to turn with said spool, a gear en- 35 meshed with said pinion, means connected with said gear, whereby to turn said pinion and spool, and an oil chamber in said spool through which chamber said shaft projects 40 for allowing its bearing parts to be lubri- cated, and a spring pressed ball for closing the opening to said chamber.

6. In a casting reel, a rotatable spool, a casing for enclosing said spool, a pinion 45 mounted to turn with said spool, a gear mesh- ing with said pinion for turning said spool, a rock lever for withdrawing said gear from said pinion, whereby to allow said spool to turn at will, said casing and said rock lever 50 being provided with apertures to permit the operator to insert his finger therethrough, whereby to control the turning of said spool.

In testimony whereof I affix my signature.

GUSTAF A. JOHNSON.
